SEWING MACHINE

Richard William Johnson, Charles Lester Lov-
erch, and Max Zaum, Brooklyn, N. Y., assignors
to Fine Art Novelty Corporation, New York,
N. Y., a corporation of New York

Application March 1, 1937, Serial No. 128,360

4 Claims. (CL. 112—79)

This invention relates to improvements in sewing machines. One of the objects of the invention is to provide a sewing machine capable of producing a series of discontinuous U-shaped loops of yarn, the ends of which are free from adjacent loops. A further object is to provide an attachment for the underside of the cloth plate of a sewing machine, wherein the loop-taker forms part of a shearing mechanism which shears once for each complete reciprocation of the needle.

A more detailed description follows in conjunction with the drawing, wherein like reference numerals designate like parts.

Fig. 1 illustrates a front end elevation, partly in section, showing only that portion of a sewing machine equipped with the present improvement which is necessary for an understanding of the invention;

Fig. 2 is a full size view of the essential elements of the shearing attachment of the invention;

Fig. 3 is a side view of Fig. 2, along the line 3—3, with the bed or supporting portion of the sewing machine in section;

Fig. 4 is a cross-sectional view of Fig. 2 along the line 4—4;

Figs. 5a, 5b, and 5c are perspective detail views showing progressive positions of the shearing mechanism of the invention in the process of making and shearing a loop of yarn. The dot and dash lines of Fig. 5c show the actual shearing position;

Fig. 6 is a cross-sectional view of Fig. 5c along line 6—6, and shows the position of the shearing knife and looper immediately before the yarn is cut; and

Figs. 7a to 7f show diagrammatically, and in section, the progressive positions of the needle in the cutting of the yarn. The positions of the loop-taker and knife are omitted from Figs. 7a, 7b, and 7c, in order to simplify an understanding of the complete cycle of operations.

Referring to Fig. 1 in more detail, the sewing machine in which the invention has been embodied is shown as comprising a hollow standard which curves and terminates in a head 2. Mounted for vertical movement in the head 2 by the manual manipulation of the lifting lever 3 is the usual presser-bar 4 carrying one or more presser feet 5. The hand or band wheel is represented by the reference numeral 6. Secured in the usual manner to a vertically reciprocating needle bar by means of a needle clamp 7 is the

eye pointed needle 8 accommodating a suitable thick yarn 9.

The feeding mechanism comprises a feed-dog 10 operating through suitable slots in a throat-plate mounted on cloth-plate 11. Feed-dog 10 is carried by the feed-bar 12, which is, in turn, actuated in any suitable well known manner to provide a single feeding movement of the feed-dog during a part of the cycle of operation of the vertical reciprocating needle 8. As feeding mechanisms of this character are well known in the art, it is deemed unnecessary to herein describe such a mechanism for a complete understanding of the present invention.

The shearing mechanism of the invention, which is shown in more detail in Fig. 2, is mounted underneath the bed plate and comprises, as separate elements, a loop-taker 13 and a fork-shaped knife 14.

The loop-taker consists of a massive shoulder 20 having integral therewith a smooth, round finger or beak 19 provided with a shearing edge 22 along a portion of the inner surface, as shown. At its center, loop-taker 13 very loosely accommodates the looper actuating shaft 15 but is firmly linked to shaft 15 at another point by means of off-center screw 16 which is set into a lug 17 of a metallic bushing 17, in turn surrounding the shaft for a portion of its length and secured thereto by means of screw 18. Movably linked to loop-taker 13 by the same screw 16 is fork-shaped knife 14 whose knife edge 21 is designed to cooperate with the shearing edge 22 of finger 19. Knife 14 is maintained in position between the loop-taker 13 and a spring washer 23, the latter of which separates the arch of the knife from the screw 16 in such manner that as the loop-taker rotates, the knife is caused to move relative to the loop-taker and to assume various positions. A roller 24 located between the two tines of the fork-shaped knife, and held in place by screw 25 to the bed 26 of the sewing machine, serves to guide the movement of the knife as it is lowered and raised by rotation of the loop-taker.

Figs. 3 and 4 show side and cross-sectional views of Fig. 2, respectively, along the lines 3—3 and 4—4, and illustrate more clearly the manner in which the loop-taker 13, fork-shaped knife 14, and the actuating shaft 15 are linked together.

From what has gone before, it will be evident that when the finger 19 of the loop-taker is on its upward travel, the shoulder 20 of the loop-taker will be on its downward travel and will

cause knife 14 also to move downward, guided by roller 24. The arrows in Fig. 2 indicate the directions of travel at a particular position of the elements 13 and 14. Movement of the loop-taker in the opposite direction will, of course, produce a similarly opposite movement of the knife 14. It will also be evident that at another point in the travel of the loop-taker 13, shown in Fig. 1 and by the dotted lines of Fig. 5c, the 10 knife edge 21 of knife 14 and the shearing edge 22 of loop-taker 13 will come together and cause shearing of any yarn which may happen to be between the two shearing surfaces at that moment. Fig. 6 illustrates a cross-sectional view of 15 the shearing surfaces 21 and 22 immediately prior to the cutting of the yarn 9.

Figs. 5a, 5b, and 5c show progressive positions of the loop-taker 13 and knife 14 as the needle first descends to form a loop of yarn which is 20 seized by the finger 19 and then rises to enable the shearing to take place and the feeding of the work to occur.

In the operation of the invention, as indicated diagrammatically in Figs. 7a to 7f, the 25 needle 8 is caused by its well known actuating mechanism to penetrate the material or work 26 immediately following the first forward feeding movement of the feed-dog 10, descending below the work to throw out a loop of yarn in 30 proper position for seizure by the loop-taker finger or beak 19. Fig. 7a indicates the downward travel of the needle. Fig. 7b shows the needle at its lowest position, and Fig. 7c indicates the start of the upward travel of the needle. In these 35 three figures the positions of the loop-taker 13 and the knife 14 have been omitted in order to avoid complicating the drawing, because the finger 19 has not, up to this time, in the travel of the needle seized the loop of yarn. Fig. 7d shows 40 that the smooth round portion of finger 19 enters the loop after the needle has started to rise. In other words, the needle after descending has been slightly raised and a loop of yarn is thus formed which is immediately entered by the finger 19. In Fig. 7e the needle has risen above the work and the shearing surfaces are about to engage. Fig. 7f shows the position of the shearing surfaces immediately after the yarn has been cut. Subsequent to this the surfaces 21 and 22 progressively separate, a lateral feeding movement of the work takes place, and the cycle of operations of Figs. 7a to 7f is repeated.

It is important to note in the cycle of operations indicated in Figs. 7a to 7f, for producing a U-shaped loop of yarn, that the feeding of the work occurs only once in every complete reciprocation or cycle of the needle. An inspection of Figs. 7a to 7f shows, of course, that the needle descends below and rises above the work in the same hole pierced by it.

In one embodiment of the invention, the pres-

ent improvement has been applied to a well known type of sewing machine wherein the loop-taker actuating shaft 15 oscillated first in one direction and then in the other, the shearing occurring only during one direction of travel of the 5 shaft and the feeding during the other direction of travel of the shaft.

What is claimed is:

1. In a sewing machine, the combination with a reciprocating needle and a loop-taker actuating shaft, of a yarn shearing mechanism rotatable by said shaft, said mechanism comprising a loop-taker having a shearing surface and a fork-shaped knife eccentrically mounted on and movable with said loop-taker, relatively stationary means between the tines of said forked-knife for guiding the movement of said knife, said knife and said shearing surface of said loop-taker cooperating to cut yarn carried by said needle at a predetermined position of said loop-taker. 20

2. In a sewing machine, the combination with a vertically reciprocating needle and a horizontal loop-taker actuating shaft, of a loop-taker substantially in the form of a circle with a segment removed, said loop-taker having a central 25 hole loosely accommodating said shaft, approximately half of said circle being in the form of a curved finger for forming a loop of yarn, the remaining portion of said circle being wider than said finger and extending from the circumference to said hole, said finger having a shearing surface on a portion removed from its free end, a fork-shaped knife mounted on the wider portion of said loop-taker and movable with said loop-taker, said knife having a shearing edge 30 and a pair of separated tines, a relatively stationary roller located between said tines for guiding movement of said knife, the shearing edge of said knife and the shearing surface of said finger being adapted to cooperate at a predetermined 35 location in the path of travel of said loop-taker to form yarn shearing mechanism. 40

3. In a sewing machine, the combination with a reciprocating needle and a loop-taker actuating shaft, of a yarn shearing mechanism rotatable by said shaft, said mechanism comprising a loop-taker having a shearing surface and a fork-shaped knife mounted on and movable with said loop-taker, a roller positioned between the tines of said fork-shaped knife for guiding the movement thereof, the arch of said knife and said shearing surface of said loop-taker cooperating to cut yarn carried by said needle at a predetermined position of said loop-taker. 50

4. A sewing machine as defined in claim 3, 55 characterized in this that said shaft oscillates in two directions of travel.
